UNITED STATES PATENT OFFICE.

AXEL A. STROM, OF AUSTIN, ILLINOIS, ASSIGNOR TO THE WALMSLEY & COMPANY, OF CHICAGO, ILLINOIS.

ACETYLENE-GAS APPARATUS.

SPECIFICATION forming part of Letters Patent No. 628,641, dated July 11, 1899.

Application filed December 16, 1898. Serial No. 699,439. (No model.)

To all whom it may concern.

Be it known that I, AXEL A. STROM, a citizen of the United States, residing at Austin, in the county of Cook and State of Illinois, have invented a new and useful Improvement 55 in Acetylene-Gas Apparatus, of which the following is a specification.

The objects of this invention are to improve acetylene-gas apparatus in matters of detail, 10 to overcome defects, and produce an automatic apparatus for supplying acetylene gas to the consumer which shall be thoroughly reliable and safe in operation.

Referring to the accompanying drawings, 15 Figure 1 shows my improved apparatus by a view in elevation, with a part broken away to disclose a detail. Fig. 2 is a section taken at the line 2 on Fig. 1 and viewed in the direction of the arrow; Fig. 3, a broken section 20 taken at the line 3 on Fig. 2 and viewed in the direction of the arrow; Fig. 4, a perspective view of the cover of the carbid-holder, showing details; Fig. 5, a section taken at the line 5 on Fig. 2 and viewed in the direction of the arrow; Fig. 6, a section taken at the line 6 on Fig. 2, viewed in the direction 25 of the arrow and enlarged; Fig. 7, an enlarged view, in sectional elevation, of the siphoning water-supply mechanism to the carbid-holder from the gas-holder, the section being taken at the line 7 on Fig. 8 and viewed in the direction of the arrow; and Fig. 8, a broken section taken at the line 8 on Fig. 2, viewed in the direction of the arrow and enlarged. 35

A is the outer stationary tank of a gas-holder, and B is the inner inverted tank or bell, shown as having an inclined top *r* with the body of the bell extended above it to 40 form an annular shield *r'*, for a purpose hereinafter described, and as having fastened to it a central depending guide-pipe *p*², provided at its lower end with a stop-flange *q* and telescoping with a stand-pipe *p*, extending vertically upward from the center of the base of 45 the tank A, being provided at its upper end with a stop-flange *q'* to be engaged by that on the guide-pipe *p*² for limiting the extent of rise of the bell. Within the tank A at a desired distance above its base and confined 50 around the pipe *p* is a diaphragm affording

a false bottom *o* and forming between it and the bottom of the tank a space to provide a condenser C, into which, preferably near its vertical center, as shown, or at all events below the surface of the water therein, the pipe *p* opens, as at *v*, Fig. 5. The condenser is supplied with water through an overflow-spout *n*, communicating with it near its base, at one side, and reaching upward beyond the 60 plane of the false bottom *o*, forming the top of the condenser.

A gas-inlet pipe *m* extends upward from the false bottom *o* (through which it communicates with the condenser) in the tank A and 65 beyond the line (indicated at *x*, Fig. 5) of the supply of sealing-water in the bell B, the water for the seal between the two members A and B being supplied at a spout *n'* on the tank A, as shown in Fig. 5. The outlet-pipe 70 for gas in the bell is shown at *l*, rising from the false bottom *o* above the water-line *x* and projecting at its lower end some distance into the condenser to be immersed normally in the water therein. A branch pipe *l'* leads from 75 the pipe *l* out through the wall of the tank A to conduct the gas away for use, and a branch pipe *p'* leads from the pipe *p* into the open air to afford a safety-escape, as hereinafter described, for surplus pressure of gas beyond 80 the predetermined pressure thereof, for holding which the apparatus is arranged.

The supply of gas as it is generated enters the condenser C through a pipe *k*, which passes into the tank A through its wall above 85 the plane of the condenser, and where the pipe *k* opens into the condenser through its top it is surrounded by an annular collar depending from the top into the body of condenser-water, below the level of which it is 90 provided with numerous small perforations to afford a subdivider *i* for the gas, all of which that is generated must pass through it before entering the pipe *m* from the condenser to attain the holder-space in the bell B. The 95 provision of the device *i* by dividing the gas into fine streams as it enters the condenser-water tends to prevent pulsations thereof in the holder and consequent flickering at the burners where the supply leads directly there- 100 to through the pipe *l*.

D is the carbid-holder, comprising a recep-

tacle (or "pail") h , supported adjacent to the tank A, as on feet t , depending from its base. The top h' of the receptacle h is rounded and of somewhat conical shape and has its opening h^2 formed on an incline, as represented, and surrounded by a collar h^3 , affording a seat for the cover h^4 , rounded transversely about its upper edge to prevent the accumulation upon it of residue from emptying the receptacle. On the top of the cover are shown hollow enlargements g^2 g^3 , forming chambers g and g' , from the latter of which depends a water-discharge nipple g^4 , and about the under side of the cover is shown a rubber gasket w , at which to bear against the collar h^3 . The outer end of the pipe k enters the cover-chamber g and carries the cover in rigid inclined position corresponding with the inclination of the receptacle-opening h^2 , this pipe being reinforced by a rigid hanger-bar k' , connected at its lower end with a collar k^2 , surrounding the pipe, and fastened at its upper end to the outer side of the tank A. By this construction the receptacle h is removable from its stationary cover, whereby it is uncovered and ready to be dumped on merely withdrawing it, and by shoving it back under the cover to replace it after charging with carbid closure is effected. The closure is tightened by means of a set-screw f , working in a cross-bar f' , removably confined toward its ends in vertically-slotted bearings f^2 f^3 , rising from the top h' at opposite sides of the opening h^2 therein, whereby the set-screw is caused to bear and be turned against the enlargement g^2 . The ends of the bar f' are confined against the upper closed ends of the slots in the bearings f^2 by the strain of the set-screw against the enlargement g^2 . In introducing the receptacle h into its operative position it is guided and centered by engagement of the bearings f^2 with the rounded edge of the stationary cover h^4 , from opposite sides of which project ears f^3 f^3 in the path of the bearings f^2 to be encountered by them and afford stops for the carbid-receptacle h against forcing it too far inward in replacing it.

The water to the holder D for producing the gas generation is supplied automatically at required intervals from the water in the gas-holder through a pipe d , leading at one end into the cover-chamber g' and shown as containing a shut-off cock (indicated at d') and a trap extension d^2 , and this pipe is connected at its opposite end with a siphoning device E, represented to be supported on the outer side of the tank A near its upper end and involving the following-described construction: On a tubular arm u , extending from the side of the tank with which it communicates through an opening u' , Fig. 7, near its upper end, is rigidly supported in upright position a valve device having a chamber c in a casing E' , containing a seat c^2 for an upwardly-closing piston-valve c' , having its stem c^3 passing upward through a guide

extension c^4 of the casing into alignment with the head a' of an operating-rod a , carrying a weight a^2 at its upper end and yieldingly supported in a vertical guide-sleeve a^3 on the overhanging end of an arm a^4 , rigidly fastened to the top r of the bell B. The valve c is normally held to its seat by the force of a spring c^6 , confined against it from underneath. With the casing E' there is connected by a passage c^5 from the chamber c therein above the piston a casing E^2 , to the lower end of which the upper end of the pipe d is coupled, this casing containing between its ends below the plane of the passage c^5 a diaphragm b' , dividing it into chambers b^2 and b^3 , and into an opening in which is fastened one end of a siphon-pipe b , and from the chamber b^2 leads a vent-pipe b^4 .

To start the apparatus, the gas-holder is supplied with water and the condenser C is filled with water. At this time the bell B, being at its lowest position, brings the weighted rod a to bear on the valve-stem c^3 and holds the valve open to produce a water-passage from the tank A to the nipple at the chamber g' of the cover h^4 in the carbid-holder through the pipe d and siphon device E, interposed in it. After the start (for which the chamber b^3 should be preparatorily supplied with water by pouring it into the same) there will always be a supply of water in the siphon-chamber b^3 to automatically produce the siphoning action whenever the valve c is opened by the fall of the bell B to the required extent; but the siphon action will not, of course, start the flow until the chamber b^3 fills to the height of the pipe b therein.

The gas that is evolved from the calcium carbid in the holder D by the fall of water upon it from the nipple g^4 passes out through the pipe k into the perforated collar i , whence it escapes in finely-divided streams through the perforations into the condenser C. From the condenser the gas passes up through the pipe m into the bell B, which exerts the predetermined pressure at which the gas is to be delivered through the pipes l l' . As the gas-holder fills the gas accumulation in the bell raises it, and when the accumulation of gas is sufficient to raise it to its limit, so that further accumulation increases the predetermined pressure, the surplus pressure on the surface of the water in the condenser C will depress that water, causing it to rise in, and maybe overflow at, the spout n , thereby lowering the condenser-water surface below the entrance to the escape-pipe openings v to permit the surplus pressure to discharge into the pipe p and thence into the open air through the branch p' . Thus, as will be seen, a safety pressure-escape is afforded.

In the rise of the bell the rod a is eventually lifted from the valve-stem c^3 , though not necessarily immediately, as the engagement will continue until the collar a^3 abuts against the weight a^2 to carry the rod. With the freeing of the valve-stem the spring c^6 closes the

valve, thereby shutting off the supply of water to the carbid-holder D until the supply of gas in the bell B becomes so far exhausted as to cause it to drop far enough to produce reengagement of the rod *a* with the valve-stem *c*³.

As will be observed, the automatic supply of water from the gas-holder to the carbid-holder is not measured, nor predetermined, nor uniform, since it will always be in accordance with the length of time the valve *c*³ remains open.

The predetermined pressure in the gas-holder, which the weight of the bell B maintains, is prevented from being exceeded by possible immersion of the top *r* below the water-line *x* in the tank and consequent additional weight on the bell of the water over it by the provision of the shield *r'* around the bell-top, which extends above the lowest plane to which the bell may drop in the tank.

By the foregoing construction the following more important advantages, in addition to those mentioned, are attained: The supply-pipe *k* of gas from the carbid-holder to the gas-holder is always water-sealed, thereby preventing the escape of gas when the receptacle *h* is removed, and the connecting-pipe *d* between the holder D and water-supply from the tank A is likewise always sealed, thereby preventing the escape of gas from the carbid-holder. The overflow on the condenser, extending above the highest possible water-level therein, regulates the water-level whether the water in the condenser be added to from condensation in the pipes communicating with it or the level be varied by excess of gas-pressure in the holder. The supply of water for the carbid in its holder D is always taken from a fixed point in the gas-holder, thereby preventing the water seal from being broken between the tank A and bell B when the bell is up high. The inclined fixed cover cooperating with the correspondingly-inclined seat about the opening in the carbid-receptacle obviates any joints for swinging the cover to permit removal of the receptacle, and the rounded outer edge of the collar *h*⁸ prevents accumulation of residue at the junction of the cover with its seat and consequent impairment of the gasket and leakage.

The construction shown and described of the various parts and the particular manner of their combination may, without departure from my invention, be modified and changed in different ways by those skilled in the art. Hence I do not limit my invention thereto.

What I claim as new, and desire to secure by Letters Patent, is—

1. In an acetylene-gas apparatus, the combination with the gas-holder of a condenser in the bottom of the stationary tank communicating with the gas-supply and provided with an overflow, a pipe leading from the condenser above the water-line in said holder, and a pipe extending from within the condenser in the gas-holder and open to the condenser below the normal water-line therein and provided

with an outlet branch, substantially as described.

2. In an acetylene-gas apparatus, the combination with the gas-holder of a condenser in the bottom of the stationary tank communicating with the gas-supply and provided with an overflow, a pipe leading from the condenser above the water-line in said holder, a stand-pipe rising through the condenser in the gas-holder and open to the condenser below the normal water-line therein, an outlet branch leading from said stand-pipe to the outer air, and a pipe depending from the bell and telescoping said stand-pipe, substantially as described.

3. In an acetylene-gas apparatus, the combination with the gas-holder of a false bottom in the base portion of the tank forming a condenser therein, communicating with the gas-supply, an overflow-spout on the condenser extending above the plane of its top, a gas-inlet pipe extending from the condenser beyond the water-line in said holder, a gas-outlet pipe extending from beyond said water-line through the condenser below its top and leading out of the holder, a stand-pipe rising through the condenser in the gas-holder and open to the condenser below the normal water-line therein, an outlet branch leading from said stand-pipe to the outer air, and a pipe depending from the bell and telescoping said stand-pipe, substantially as described.

4. In an acetylene-gas apparatus, the combination with the carbid-holder, of a water-supply communicating with said holder, a valve-controlled siphon device interposed in the communication and having a siphon-pipe adapted to be immersed to the highest point of its bore in the water to be siphoned, and means operated by the movement of the gas-holder bell to open the valve of said siphon device, substantially as described.

5. In an acetylene-gas apparatus, the combination with the carbid-holder, of a water-supply having a trapped pipe communication with said holder, a vent-equipped siphon device interposed in said pipe and having a siphon-pipe adapted to be immersed to the highest point of its bore in the water to be siphoned, and means operated by the pressure of gas in the gas-holder to regulate the water-supply through said siphon device, substantially as described.

6. In an acetylene-gas apparatus, the combination with the stationary tank of the gas-holder and a carbid-holder having water-pipe communication with said tank at a fixed point below the normal water-line therein, of a valve-controlled siphon device interposed in said communication and having a siphon-pipe adapted to be immersed to the highest point of its bore in the water to be siphoned, and means operated by the movement of the bell to open the valve of said siphon device, substantially as described.

7. In an acetylene-gas apparatus, the combination with the stationary tank of the gas-

holder and a carbid-holder having water-pipe communication with said tank at a fixed point below the normal water-line therein, of a valve-controlled siphon device in said communication comprising a casing containing a chamber and a valve therein, a casing divided into two chambers intercommunicating through a siphon-pipe in one chamber, which communicates with the valve-chamber, and a vent-pipe leading from the other chamber, and means operated by the movement of the bell to open said valve, substantially as described.

8. In an acetylene-gas apparatus, the combination with the stationary tank of the gas-holder and a carbid-holder, of a siphon device comprising a casing having a tubular communication with said tank at a point below its normal water-line and containing a chamber provided with a spring-controlled valve provided with a stem projecting beyond said casing, a casing divided into an upper chamber, communicating with said valve-casing and containing a siphon-pipe, and a lower chamber provided with a vent-pipe and communicating with said upper chamber through the siphon-pipe, a trapped water-pipe leading from said lower chamber to the carbid-holder, and a weighted rod yieldingly supported on the gas-holder bell to engage said valve-stem, substantially as described.

9. In an acetylene-gas apparatus, a carbid-holder comprising a stationary cover having a stop projecting laterally from its edge, and a carbid-receptacle having a stop to engage the cover-stop, said cover presenting a guide to the stop on the receptacle in sliding the latter into place underneath the cover, substantially as described.

10. In an acetylene-gas apparatus, the combination with the gas-holder, of a carbid-holder for supplying gas to the gas-holder, having a receptacle provided with a base on which it is removably supported adjacent to

the stationary tank of said gas-holder and having an inclined opening, and a cover secured in inclined position to fit and be wedged against said opening by sliding the receptacle on its base beneath said cover, substantially as described.

11. In an acetylene-gas apparatus, the combination with the gas-holder, of a carbid-holder for supplying gas to the gas-holder, comprising a receptacle provided with a base on which it is removably supported adjacent to the stationary tank of said gas-holder and having an inclined opening in its top surrounded by a collar forming a cover-seat, bearings rising from said top at opposite sides of the opening, cover-fastening means connected with said bearings, a cover rigidly secured in inclined position to fit and be wedged against said collar by sliding the receptacle on its base underneath the cover, and stops on the cover for engagement with said bearings, substantially as described.

12. In an acetylene-gas apparatus, the combination with the gas-holder, of a carbid-holder comprising a receptacle removably supported adjacent to the stationary tank of said gas-holder, and having an inclined opening in its top surrounded by a collar forming a cover-seat, a cover rigidly connected with said tank in inclined position to fit upon said collar and provided on its under side with a seating-gasket, a chamber on said cover opening to said receptacle and having a gas-supply-pipe connection with the gas-holder, a chamber on said cover having a depending water-discharge nipple leading to said receptacle and a water-pipe connection with the gas-holder, and means for fastening the cover against its seat, substantially as described.
